UNITED STATES PATENT OFFICE.

SAMUEL W. BELK, OF WALLINGFORD, CONNECTICUT, ASSIGNOR TO SIMPSON, HALL, MILLER & CO., OF SAME PLACE.

DESIGN FOR HANDLE FOR SPOONS, FORKS, &c.

SPECIFICATION forming part of Design No. 12,241, dated May 3, 1881.

Application filed March 15, 1881. Term of patent 7 years.

To all whom it may concern:

Be it known that I, SAMUEL W. BELK, a citizen of the United States, residing at Wallingford, in the county of New Haven and State of Connecticut, have invented and produced a new and original Design for the Handle of Spoons, Forks, &c., of which the following is a specification, reference being had to the accompanying drawing, forming part thereof, in which is represented a front view of a fork having my newly-designed handle.

The invention relates to a design for the handle of spoons, forks, and like articles of table-service; and it consists in the peculiar configuration of the inclosure formed by the fillet on each side of the upper part of the handle, and in a panel at the tip, in connection with the representation of a series of crowns under said panel.

It consists, also, in the representation upon the handle, above the central boss thereof, of a spherical flower pot or vase containing a standing plant.

Heretofore the upper part of spoon and fork handles has been made gradually expanding in two curved lines, and a curved fillet gradually tapering toward the central portion has been used upon them. Other handles have been made with straight sides and fillets parallel with said sides.

The representation of a standing plant has also been used as an ornament upon the handle; but my design differs in many respects from all made previously.

To describe the invention more fully, starting from the body of the article, the handle is provided nearly half-way of its length with a boss, *a*, having three ornaments, each one showing four leaves, and under said boss is shown a half-open fan, *b*. Above the boss *a* the handle gradually expands in two straight lines, *c c*, terminating in two concave curves, *d*, in the form of a quarter of a circle, united by

two straight lines, *e*, converging together in the center of the tip. Between the sides *e* are placed straight fillet-lines *f*, starting from the outer end of lines *e*, and extending nearly down to the boss *a*, converging there with the sides *e*; and between the edges *e* and fillets *f* are embossed a series of ornamental figures, gradually diminishing in size toward said boss *a*. Within the obtuse angle formed by the tip lines *e* zigzag lines are embossed, and in the central panel under them four crowns, *g*, are represented; and under said panel is shown a number of stars in line, with hanging drops between them. Between the fillets *f*, and directly above the boss *a*, is placed upon an ornamented support a spherical flower-pot, *h*, projecting above its base, and containing a standing plant showing a series of radiating leaves.

I claim—

1. The herein-described design for articles of table-service, consisting of a handle gradually expanding in two straight lines, *c c*, and provided with straight fillets *f*, diverging from the edge lines *e*, with a series of ornamental figures placed between the converging lines *e* and *f*, and gradually diminishing in size toward the boss *a*, substantially as shown and described. 65 70

2. The design for articles of table-service, consisting of a handle having two converging fillets, *c f*, near each edge, and a panel in the upper end, within which a series of crowns are placed, substantially as shown and described. 75

3. The design for articles of table-service, consisting of a handle having two converging fillets, *c f*, near each edge, and a spherical vase containing a standing plant between the inner fillets, *f*, substantially as shown and described. 80

SAMUEL W. BELK.
